(57) **CLAIM**

The ornamental design for a seat body for chair, as shown and as described.

DESCRIPTION

FIG. 1 is a front perspective view of a seat body for chair showing my new design;

FIG. 2 is a front view thereof;

FIG. 3 is a back view thereof;

FIG. 4 is a left end view thereof;

FIG. 5 is a right end view thereof;

FIG. 6 is a top view thereof;

FIG. 7 is a bottom view thereof;

FIG. 8 is a rear perspective view thereof;

FIG. 9 is a front perspective view thereof, shown with environmental subject matter; and,

FIG. 10 is a front perspective view of a second embodiment of the seat body for chair, shown with environmental subject matter.

The broken lines in FIG. 9 and FIG. 10 of the drawings illustrate environmental subject matter that forms no part of the claimed design.

The straight dash-dot broken lines and the triangular broken lines shown in FIG. 1 to FIG. 9 of the drawings represent a stitching pattern that forms part of the claimed design.

The dotted, horizontal, and triangular broken lines shown in FIG. 10 represent a stitching pattern that forms part of the claimed design.
